UNITED STATES PATENT OFFICE.

HUGO PICK, OF CHICAGO, ILLINOIS.

DESIGN FOR A DRINKING-GLASS.

44,616.

Specification for Design.

Patented Sept. 2, 1913.

Application filed December 9, 1912. Serial No. 735,849. Term of patent 14 years.

To all whom it may concern:

Be it known that I, HUGO PICK, citizen of the United States, residing at Chicago, in the county of Cook and State of Illinois, have invented a new, original, and ornamental Design for a Drinking-Glass, of which the following is a specification, reference being had to the accompanying drawing, forming a part hereof.

This invention has for its object to provide a novel and ornamental design for a drinking glass.

The accompanying drawing illustrating my design is a perspective view of a drinking glass embodying the same.

I claim:

The ornamental design for a drinking glass as shown.

HUGO PICK.
